UNITED STATES PATENT OFFICE.

THEODORE F. NOVY, OF CHICAGO, ILLINOIS.

CLAMP FOR COLUMN-MOLDS.

1,280,820.

Specification of Letters Patent.

Patented Oct. 8, 1918.

Application filed March 19, 1917. Serial No. 155,663.

To all whom it may concern:

Be it known that I, THEODORE F. NOVY, a citizen of the United States, and resident of Chicago, in the county of Cook and State of Illinois, have invented certain new and useful Improvements in Clamps for Column-Molds, of which the following is a full, clear and exact specification.

This invention relates to improvements in clamps for column molds, that is to say clamps for producing a water tight joint between the longitudinally meeting edges of the mold for preventing the formation of a seam and seams lengthwise of the column, and for which purpose the joint is provided with outwardly projecting flanges heretofore necessarily notched for securing the clamp in its operative position and for its subsequent detachment.

20 The prime object of this invention broadly stated is to provide a column mold with a clamp, which is adapted to dispense with the notching of the flanges and so constructed that it may be conveniently attached and detached in the quickest possible time, and which when in its operation will effectually prevent any leakage whatever at the joint.

25 A further object of my invention is to provide a column mold with a clamp for securing together and tightening the longitudinal joint of a mold, the opposing jaws of which are adjustable on a hook shaped bolt forming one member of the tightening device, and which at the same time is adapted to prevent the disconnection of the jaws from each other, and whereby a single pair of adjustable clamps are adapted to extend from end to end of a column mold of any given 40 height, and this whether continuous or in sections.

Another object of my invention is to provide a column mold clamp with means adapted to form a bearing for the hook bolt, 45 and at the same time limit the closing movement of the jaws, and form a stop preventing a twist or torsional movement of the jaws, and maintaining the opposing faces in parallel planes.

50 With these ends in view, my invention finds embodiment in certain features of novelty in the construction, combination and arrangement of parts by which the said objects and certain other objects are attained, 55 all as hereinafter fully described with refer-

ence to the accompanying drawings, and more particularly pointed out in the claims.

In said drawing:

Figure 1 illustrates in front elevation a clamp for a mold in which my invention finds its embodiment.

Fig. 2 is a transverse section on the line 2—2 of Fig. 1.

Fig. 3 is a detail side elevation of the clamp in its operative position upon the joint of a column mold.

Fig. 4 is an enlarged detail front elevation of the clamp in its operative position, and

Fig. 5 is a detail transverse section showing the form of the joint connection between the longitudinal edges of the mold.

Similar characters of reference indicate the same parts in the several figures of the drawing.

For forming a joint between the longitudinal edges of a column mold the metal of one edge portion 6 is bent upon and against itself as indicated at 7, and thence at a right angle to form a flange 8.

The metal of the opposing portion 9 is provided with an outward bend 10, whence the metal projects as at 11 in a plane parallel with the surface of the bent member 7, and merges into a flange 12 projecting at a right angle thereto, and which in turn is provided with a short right angle bend 13 along its outer edge adapted to overlap the edge of the flange 8.

The outward bend 10 of the member 8 provides a stop for the opposing edge of the portion 6.

With the edges of the mold thus constructed it will be seen that not only is the inner surface of the mold substantially continuous, but that on the compression of the flanges a tight joint may be formed preventing any leakage from the mold tending to produce either a projection or groove in and longitudinally of the column molded therein.

As a means for producing and maintaining such a joint my invention includes the employment of opposing clamping jaws 14 and 15, the length of which corresponds with the predetermined height of the column mold, the shanks 16 and 17 of which jaws project laterally in planes parallel with the clamping faces of the jaws to which they are riveted, as indicated at 18, or otherwise rigidly secured.

One or the other of said shanks, as for example the shank 16 is provided with a portion 19 bent at a right angle thereto for providing a stop limiting the movement of the outer ends of the shanks 16 and 17 toward each other, and maintaining the clamping face of the jaws in parallel planes, and therefore against a rocking movement when they are tightened against the flanges, and to which they would otherwise have a tendency owing to the fact that for convenience of operation the jaws are supported and adjustable upon a hook bolt 20, the bearing portion in which for the jaws is located some distance outwardly from both jaws.

For convenience of assembling the jaws, or if need be disconnecting them, the shank of the hook bolt is screwthreaded and provided with a nut 21.

The hook bolt 20 and its hook portion 22 is adapted to confine a wedge 23, the opposing edges of which respectively bear against the hook and against the shank 17, and between which when once inserted, the wedge 25 is supported, and on being forced downwardly to a tightened position, moves the clamps toward and tightens the flanges of the mold between them.

It is now to be observed that the width of the clamping jaws corresponds with the width of the flanges of the mold to be clamped between them, and that notwithstanding the force for operating the clamping jaws is applied outwardly therefrom, and as must be in order that their width may correspond with the predetermined width of the flange, the clamping surface of the jaws is compelled to move in parallel planes and thereby uniformly compress and tighten the flanges throughout their length.

The construction of a clamp of my invention as herein shown and described provides a means for forming a water tight joint between the sections of a mold, preventing the formation of a bead or seam on a cement column, the removal of which, as must be, mars the appearance of the column, and a clamp which is not only strong and durable, but which may be secured in its operative position and removed therefrom in the

quickest possible time, with the exercise of the least amount of skill on the part of the operator, and whereby the cost of its construction and the time required for erecting the mold in its operative position is reduced to a minimum.

Having described my invention, what I claim and desire to secure by Letters Patent is:

1. A clamp comprising in combination clamping jaws, a hook-bolt projecting beyond and connected with said jaws, a wedge coöperating with said hook-bolt to tighten the jaws and means for maintaining the clamped surfaces of said jaws in parallel planes in their clamped position.

2. A clamp comprising in combination a number of clamping jaws, a number of shanks projecting at intervals therefrom in parallel planes, means for maintaining said shanks in said planes throughout tightening of the jaws, a hook-bolt passing through said shanks, and a wedge passing therethrough, adapted to tighten the jaws.

3. A clamp comprising in combination opposing clamping jaws provided at the outer ends of their shanks with stops for maintaining parallelism of the clamping surfaces of the jaws, and a tightening means located between the jaws and said stop.

4. A clamp comprising in combination opposing jaws, shanks therefor at spaced intervals, one of which is provided with an inwardly projecting flange adapted to engage opposing shanks and form a stop maintaining the clamping surfaces of the jaws in parallel planes in their tightened operative position, a hook-bolt passing through said shanks at a point removed from the jaws, and a wedge located between one of said shanks engaging said hook for closing and tightening the jaws in their operative position.

In witness whereof, I have hereunto set my hand and affixed my seal, this 28th day of February, A. D. 1917.

THEODORE F. NOVY. [L. S.]
